UNITED STATES PATENT OFFICE.

HERMAN WERTZ, OF NEWARK, NEW JERSEY, ASSIGNOR TO HARDMAN RUBBER COMPANY, A CORPORATION OF NEW JERSEY.

DISPLAY-BOX.

SPECIFICATION forming part of Letters Patent No. 714,544, dated November 25, 1902.

Application filed March 13, 1902. Serial No. 98,018. (No model.)

To all whom it may concern:

Be it known that I, HERMAN WERTZ, a citizen of the United States, residing at Newark, in the county of Essex and State of New Jersey, have invented certain new and useful Improvements in Display-Boxes; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 The present invention has reference to improvements in boxes or packages for the storing and displaying of manufactured articles; and the invention has reference more particularly to a novel construction of box for

20 the arrangement therein of a water-bottle and its long and flexible piece of tubing, the various parts of the box being arranged in such a manner that the article of manufacture can be easily arranged and held in its proper po-

25 sition within the body of the box against displacement when displaying the goods in the box to be placed at an angle in a window or while the salesman is showing the goods to a prospective purchaser.

30 The present invention therefore has for its principal objects to provide a novel construction of display-box in which the article is arranged and sold directly with the box to the purchaser; and, furthermore, this invention

35 has for its further object to provide a neat, cheap, and simply-constructed box for the purposes abovestated and provided with compartments in which the usual forms of nozzles to be used with the flexible tubing may

40 be placed.

The invention therefore consists in the novel construction of display-box hereinafter fully set forth; and, furthermore, the invention consists in the several novel arrangements and 45 combinations of parts, all of which will be described in detail in the following specification and then finally embodied in the clauses of the claim.

The invention is clearly illustrated in the 50 accompanying drawings, in which—

Figure 1 is a plan view of the display-box embodying the principles of the present invention, illustrating in connection therewith the manner of arranging the water-bottle and its flexible tubing in their properly-retained positions in the box. Fig. 2 is a longitudinal central vertical section of the box, representing a pair of pivotally-arranged retaining members, which normally hold or retain the flexible tubing in its proper position in the 55 box against accidental displacement in their lowered or retaining positions within the body of the box; and Fig. 3 is a similar section of the box, but representing the said pivotally-arranged retaining members in their raised 60 position to permit of the removal or the placing of the article of manufacture in the body of the box. Fig. 4 is a vertical cross-section of the box, taken on line 4-4 in said Fig. 1; and Fig. 5 is a perspective view of the box with the 65 cover thereof represented in dotted outline.

Similar numerals of reference are employed in all of the said above-described views to indicate corresponding parts.

In the said drawings the reference character 1 indicates the body of the box, preferably made of cardboard, being formed with the two sides 2 and the two ends 3. The said body of the box may be of any suitable configuration in outline and in its several 75 corners may be provided with an arrangement of triangularly-constructed members or strips 4, forming suitable compartments for the reception of the nozzles or other parts of the article which is to be placed in the box. 80 The said members or strips 4, owing to their arrangement across the angles in the body of the box, also provide a large compartment 6, in which in the present case a rubber water-bottle, such as is used with fountain-syringes, 85 is to be placed. In Fig. 1 of the drawings I have illustrated such a bottle, the same being indicated by the reference character 7, and 90 8 indicates the usual coil of flexible tubing which is sold with the same, and is therefore placed in the body of the box. It has been found in practice that when a salesman displays these goods to a prospective customer or when the box and the article of manufacture therein are displayed in a store- 95 100

window the said roll of tubing becomes uncoiled, and the bottle also, being made of a soft and flexible rubber, will become arranged in an unsightly mass in the lower 5 portion of the box, and thereby presenting an unsatisfactory display of the goods. To avoid these objectionable features, I have provided the box with a retaining device, which permits of the proper placing of the 10 goods in the box as well as the removal of the same from said box and at the same time retains the bottle and the tubing in a neat position in the box, whereby the salesman can more easily show off the article of manufacture to a greater advantage, or the box 15 can be placed at an angle in a show-case or show-window without the least danger of the rubber bottle and its tubing becoming located in an unsightly and ungainly heap in the 20 bottom of the box. In the present construction the said retaining device consists, essentially, of a cross-piece 9, made at its two ends with the downwardly-extending end pieces 10, substantially as illustrated in Figs. 4 and 5 25 of the drawings. Between the outer surfaces of the said end pieces 10 and the inner surfaces of the sides 2 of the body of the box I have arranged the respective end portions 13 and 14 of a pair of curved or suitably-bent 30 members or strips 11 and 12, respectively, the said end portions 10, 13, and 14 all being held in their respective positions by means of suitable pins or rivets 15, upon which the said 35 end portions 13 and 14 of the respective members 11 and 12 are also pivotally arranged, so that the said members 11 and 12 can be made to lie directly within the body of the box, one member on either side of the cross piece or member 9, as shown in Figs. 1 and 2 of the 40 drawings, or that one or both the said members 11 and 12 can be moved in the positions represented in Figs. 3 and 5 of the drawings. To place the goods in the body of the box, the said pivotal members 11 and 12 are made 45 to assume the positions indicated in Fig. 3, which enables a person to place the flexible bottle 7 in a flat position in the body of the box, the bottle being inserted beneath the said cross piece or member 9, as will be clearly 50 understood. The two members 11 and 12 are then turned from their raised positions (indicated in said Fig. 3 of the drawings) to their lowered positions on either side of the said member 9 to lie directly within the compartment 55 6 of the box, as clearly indicated in Figs. 1, 2, and 4 of the drawings. The two members or strips 11 and 12 thereby provide an auxiliary or additional compartment 16, (see Fig. 1,) in which the flexible rubber tubing 8 is arranged in a coil, as shown, and is held in such position against accidental displacement by the circular edges of the said members 11 and 12, as will be clearly evident 60 from an inspection of said Fig. 1 of the drawings. Owing to these various arrangements of the parts of the retaining device, the flexi- 65

ble bottle 7 as well as the coil of tubing 8 will be neatly arranged and held in position in the body of the box and for the proper exhibition of the goods, as has been hereinabove 70 stated.

I am fully aware that some changes may be made in the various arrangements and combinations of the parts hereinabove described, and illustrated in the accompanying 75 drawings, without departing from the scope of my present invention. Hence I do not wish to be understood as limiting my invention to the exact arrangements and combinations of the parts as described and as illustrated in the said drawings, nor do I confine myself to the exact details of the construction of the said parts.

Having thus described my invention, what I claim is—

1. In a display-box, the combination, with the body of a box, adapted to receive an article of manufacture, and the longitudinal sides 2 of the box, of means in said box consisting of a pair of semicircular members, said members extending in opposite directions and forming a circular compartment for the reception of the article of manufacture therein, and said semicircular members being pivotally attached at their opposite end portions 90 to the inner surfaces of the said sides 2 of the box, substantially as and for the purposes set forth.

2. In a display-box, the combination, with the body of a box, adapted to receive an article of manufacture, of means in said box adapted to be brought in contact with the said article of manufacture, to retain the same in position against accidental displacement, comprising, a fixed cross piece or member 9 connected with the sides of the box, so arranged that the article of manufacture is placed beneath said member, and a pair of other members pivotally connected with the sides of the box, substantially as and for the purposes set forth.

3. In a display-box, the combination, with the body of a box, adapted to receive an article of manufacture, of a pivotal pin in each side of the box, and a pair of semicircular retaining members pivotally connected with the said pins, substantially as and for the purposes set forth.

4. In a display-box, the combination, with the body of a box, adapted to receive an article of manufacture, of a pivotal pin in each side of the box, a pair of semicircular retaining members pivotally connected with the said pins, and a cross piece or member 9 arranged between the said semicircular retaining members, said piece or member 9 having its end portions also pivotally connected with said pins, substantially as and for the purposes set forth.

5. In a display-box, the combination, with the body of a box, adapted to receive an article of manufacture, of a retaining piece or

member 9 secured in said box, beneath which
the said article of manufacture is placed, and
a semicircular retaining member located on
each side of said member 9, adapted to be
5 raised beyond the body of the box, substan-
tially as and for the purposes set forth.

In testimony that I claim the invention set

forth above I have hereunto set my hand this
11th day of March, 1902.

HERMAN WERTZ.
